UNITED STATES PATENT OFFICE

HARRY J. W. TRAUMÜLLER, OF BROOKLYN, NEW YORK

CATCH DEVICE

Application filed September 18, 1928. Serial No. 306,756.

This invention relates to catch devices and particularly to devices of this class adapted for use in connection with boxes, cases and the like; and the object of the invention is 5 to provide a catch device involving a retaining member, latch or catch plate arranged within the upper surface of the lower part of a box member or case, thus preventing the engagement of such device with the hand 10 of an individual, passed into the box in the operation of removing the contents thereof; a further object being to provide a catch device of the class described which is adapted primarily for use in connection with jewelry 15 boxes or cases of various kinds and classes, tensional means being provided to normally support the catch plate in predetermined or locked position, and means involving a button arranged externally of the box or case, 20 permitting the movement of said catch plate into inoperative position against the action of said tensional means to release the cover of the box or case; and with these and other 25 objects in view, the invention consists in a device of the class and for the purpose specified which is simple in construction, efficient in use, and which is constructed as herein-after described and claimed.

The invention is fully disclosed in the following specification, of which the accompanying drawing forms a part, in which the separate parts of my improvement are designated by suitable reference characters in each of the views, and in which:—

35 Fig. 1 is a side and sectional view of a box or case showing one form of my improved catch device mounted in connection therewith.

Fig. 2 is a plan view of the structure shown 40 in Fig. 1 with parts broken away.

Fig. 3 is a partial section on the line 3—3 of Fig. 2.

Fig. 4 is a view similar to Fig. 2 showing 45 only a part of the construction and showing a modification; and,

Fig. 5 is a view similar to Fig. 3 but showing the modification illustrated in Fig. 4.

For the purpose of illustrating one use 50 of my invention, I have shown in the accompanying drawing the separate parts 10 and

11 of a box or case which as will be apparent may be of any desired shape, form, size or contour, the part 10 representing the bottom of the box or case and the part 11 the cover. Said parts are hinged at one side as 55 seen at 12, and each part 10 and 11 may be provided with felt, velour or other facings and paddings as seen at 13, Figs. 1 and 3 of the drawing.

In the manufacture of boxes or cases of 60 the class under consideration and particularly the catch devices thereof, it has been customary to provide a movable catch or latch plate on the box member proper which projected above the upper surface of the walls 65 of the box member, thus presenting a rather sharp metallic element which oftentimes would engage the hand of a person when extended into the box member to remove an article therefrom, causing injury to the hand. 70 It is the distinctive feature of my invention to provide a device with a movable catch or latch plate contained within the boundaries of the upper face of the walls of the box member 10. 75

In the construction shown in Figs. 1 to 3 inclusive, I have indicated at 14, one of my improved catch or latch plates or members which as seen in said figures involves a top wall member 15 arranged at right angles to 80 the vertical plane of the walls of the box 10 and provided with an elongated aperture 16, said plate including a part 17 arranged adjacent the front wall 10^a of the box member 10 and provided with a button member 18 85 slidably engaging the wall 10^a and projecting outwardly therefrom to permit of the inward movement of the plate 14. This plate also includes an elongated guide portion 19 arranged in parallel relation to the bottom wall 90 10^b of the box and arranged upon a mounting plate 20 secured to the wall 10^b, said plate having oppositely disposed guide flanges 21 95 engaging opposite sides of the guide portion 19 to retain the same in proper alinement in the inward and outward movement of the plate or member 14. The inner end of the portion 19 is provided with an upwardly directed tongue 19^a stamped from the material thereof, which is adapted to engage the cen- 100

tral portion of a spring wire 22 the ends of which are retained on the plate 20 by similar tongues 20^a stamped from said plate. The spring wire 22 is normally under tension and 5 serves to support the vertical wall 17 of the member 14 against the inner surface of the wall 10^a of the box and said member 14 is moved inwardly against the tension of the spring 22 by the button 18 or by the latch 10 member 23 mounted in connection with the cover 11. The member 23 is in the form of a sheet metal plate, note Fig. 3, and this plate is provided centrally with a downwardly extending and tapered catch member 23^a adapt- 15 ed to pass through the aperture 16 in the part 15 of the member 14 and further to engage said part 15 to secure the cover 11 to the box proper 10, see Fig. 1 of the drawing.

The structure shown in Figs. 4 and 5 of the 20 drawing differs primarily from that shown in Figs. 1 to 3 inclusive in the manner of mounting the latch member in connection with the box 10. In this construction, the member 14 is designated at 14^a, the top plate of said 25 member being indicated at 15^a, the aperture at 16^a, the vertical wall at 17^a and the knob or button at 18^a. The member 14^a does not include the part 19, and instead of providing the mounting plate 20, I substitute there- 30 for the mounting plate 24 which is secured to the inner face of the upright wall 10^a of the box and is provided at its ends with keepers 25 for engaging the ends of a spring wire 26, the central portion of said wire nor- 35 mally bearing upon the inner face of the up- right portion 17^a of the member 14^a to support the same in a locked position. In this construction, the member 23 is identical with that seen in Figs. 1 to 3 inclusive and in- 40 cludes the latch part 23^a adapted to engage the top plate 15^a of the member 14^a.

While I have shown two forms of construc- 45 tion for carrying my invention into effect and have also indicated one particular type of tensional means for controlling the operation of the latch member, it will be understood that I am not necessarily limited to the details of construction herein shown and de- 50 scribed, and various other changes in and modifications of the construction herein set out may be made within the scope of the ap- pended claims without departing from the spirit of my invention or sacrificing its ad- vantages.

Having fully described my invention, what 55 I claim as new and desire to secure by Letters Patent, is:—

1. A latch for boxes comprising a container and a hinged cover for closing said 60 container, one member of the latch comprising an elongated sheet metal mounting plate attached to and lying flat upon one inside surface of said container, a latch plate move- 65 able with respect to the central portion of said mounting plate, a spring rod, the ends of

which are attached to the ends of said mount- 70 ing plate and the central portion of which cooperates with said latch plate to normally hold the same in closed position, said cover having a member projecting from the lower face thereof and adapted to be engaged by 75 said latch plate to support the cover in closed position, and a pin constituting part of the latch plate and projecting outwardly through one wall of the container where- 80 by said plate may be moved under the ten- sion of said spring bar into position to re- 85 lease said member permitting the movement of the cover into open position.

2. A latch for boxes comprising a con- 85 tainer and a hinged cover for closing said container, one member of the latch comprising an elongated sheet metal mounting plate attached to and lying flat upon one inside sur- 90 face of said container, a latch plate moveable with respect to the central portion of said mounting plate, a spring rod, the ends of which are attached to the ends of said mount- 95 ing plate and the central portion of which cooperates with said latch plate to normally hold the same in closed position, said cover having a member projecting from the lower face thereof and adapted to be engaged by 100 said latch plate to support the cover in closed position, a pin constituting part of the latch plate and projecting outwardly through one wall of the container where- 105 by said plate may be moved under the tension of said spring bar into position to release said member permitting the movement of the cover into open position, said latch plate being substan- 110 tially L-shaped in cross sectional form and one flange thereof being arranged adjacent and in alignment with the top wall of the container and having an aperture through 115 which the member on said cover is adapted to pass.

3. A latch for boxes comprising a con- 110 tainer and a hinged cover for closing said container, one member of the latch comprising an elongated sheet metal mounting plate attached to and lying flat upon one inside surface of said container, a latch plate move- 115 able with respect to the central portion of said mounting plate, a spring rod, the ends of which are attached to the ends of said mount- 120 ing plate and the central portion of which cooperates with said latch plate to normally hold the same in closed position, said cover having a member projecting from the lower face thereof and adapted to be en- 125 gaged by said latch plate to support the cover in closed position, a pin constituting part of the latch plate and projecting outwardly through one wall of the container where- 130 by said plate may be moved under the tension of said spring bar into position to release said member permitting the movement of the cover into open position, and means on said mounting plate for guiding

the latch plate in its movement relatively thereto.

4. A latch for boxes comprising a container and a hinged cover for closing said container, one member of the latch comprising an elongated sheet metal mounting plate attached to and lying flat upon one inside surface of said container, a latch plate movable with respect to the central portion 10 of said mounting plate, a spring rod, the ends of which are attached to the ends of said mounting plate and the central portion of which cooperates with said latch plate to normally hold the same in closed position, 15 said cover having a member projecting from the lower face thereof and adapted to be engaged by said latch plate to support the cover in closed position, a pin constituting part of the latch plate and projecting outwardly 20 through one wall of the container whereby said plate may be moved under the tension of said spring bar into position to release said member permitting the movement of the cover into open position, means on said 25 mounting plate for guiding the latch plate in its movement relatively thereto, and means on the latch plate cooperating with said spring bar to prevent displacement of said bar with respect thereto.
- 30 In testimony that I claim the foregoing as my invention I have signed my name this 14th day of Sept., 1928.

HARRY J. W. TRAUMÜLLER.
